UNITED STATES PATENT OFFICE

GILBERT W. McDougall, of Erie, Pennsylvania

DESIGN FOR GAS METER INDICATING DIAL FACE

Application filed December 30, 1931. Serial No. 42,314. Term of patent 14 years.

To all whom it may concern:

Be it known that I, GILBERT W. McDougall, a citizen of the United States, residing at Erie, in the county of Erie and State of Pennsylvania, have invented a new, original, and ornamental Design for a Gas Meter Indicating Dial Face, of which the following is a specification, reference being had to the accompanying drawings, forming a part thereof, wherein:

Fig. 1 shows a front elevation of the meter indicating dial face showing my new design.

Fig. 2 a plan view thereof.

I claim:

The ornamental design for a gas meter indicating dial face, as shown.

GILBERT W. McDougall.
